UNITED STATES PATENT OFFICE.

HENRY BRUNT, OF BALTIMORE, MARYLAND.

DESIGN FOR A PITCHER.

SPECIFICATION forming part of Design No. 29,878, dated December 27, 1898.

Application filed November 30, 1898. Serial No. 697,914. Term of patent 3¹/2 years.

To all whom it may concern:

Be it known that I, HENRY BRUNT, a citizen of the United States, residing at Baltimore, in the State of Maryland, have invented and produced a new and original Design for Pitchers, of which the following is a specification.

Figure 1 is a side view of a pitcher having my design, and Fig. 2 illustrates a horizontal cross-section on the line 2 2 of Fig. 1.

The body A is circular, horizontally considered, and, vertically considered, has an elliptically-curved outline.

Circumferentially located on the circular body and at equal distances apart are four series of vertically-disposed volutes or corrugations, each series comprising four vertical depressions b and alternated raised portions c, the center raised portion being arched and

broad and the one on each side of the center 20 being sharp and narrow.

The rim edge d of the pitcher is scalloped, and immediately below the edge is a border of a series of modeled ornaments composed of scrolls conforming to the scallops and a 25 star-like figure located beneath the curve of each scroll.

The handle e is part elliptical in form.

Having thus described my design, what I claim is—

The design for a pitcher substantially as shown and described.

In testimony whereof I affix my signature in the presence of two witnesses.

HENRY BRUNT.
